UNITED STATES PATENT OFFICE

2,124,520

METHOD OF MAKING GALVANIZED
FERROUS PIPEFrank N. Speller, Pittsburgh, Pa., assignor to National
Tube Company, a corporation of New Jersey

Application September 1, 1936, Serial No. 98,990

3 Claims. (Cl. 91—70.2)

This invention relates to galvanized ferrous pipe, one of the objects being to increase the service life of such pipe.

According to the invention, ferrous pipe is galvanized by the conventional hot-dip method excepting that the pipe is removed from the molten zinc in a horizontal position so as to retard the gravitational flow of zinc from its surfaces, the pipe being continuously rotated during the solidification of the zinc on its surface and continuously maintained in a horizontal position until this solidification is completed. Preferably, the pipe is rotated at sufficient speed to assure a uniform distribution of the zinc over its surfaces but at an insufficient speed to assure any material centrifugal effect on this zinc. This procedure results in the pipe having relatively heavy layers of free zinc on its surfaces and in a uniform distribution of the zinc over its surfaces from end to end and on both its inside and outside.

It has been found that pure zinc provides much greater protection against corrosion than does the zinc and iron alloy which prevails at the junction between the zinc and the ferrous pipe it covers. By the above described procedure pipe is obtained having a much greater thickness of free zinc than can result when pipe is dipped by the usual methods.

A modification of the above may consist in providing a suitable means for retaining a predetermined amount of molten zinc inside the pipe, and in then rotating this pipe until solidification of the zinc is completed. This provides for a greater thickness of zinc on the inside of the pipe than can otherwise be obtained and, at the same time, assures a uniform distribution of the zinc from end to end of the pipe.

In the drawing, Figure 1 is a top plan of suitable apparatus for rotating the pipe being coated; Figure 2 is a side elevation of the apparatus of Figure 1; Figure 3 shows how the zinc may be retained in the pipe after it has been removed from the usual bath of molten zinc; and Figure 4 is a sectional view taken on the line IV—IV of Figure 3.

The apparatus illustrated by Figures 1 and 2 includes a zinc kettle 1 adapted to contain the molten zinc in which the pipe is dipped. A shaft 2 runs parallel one edge of this kettle and carries 50 arms 3 adapted to lift the pipe horizontally out

of the same, this shaft being rotated by a suitable device 4. The arms 3 may be raised into alignment with declining skids 5 which lead to a series of spaced rollers 6 powered by a motor 7 and adapted to horizontally receive the pipe 5 between them and rotate the same.

In use, the pipe is placed in the zinc in the kettle 1 for a suitable length of time and is then removed by raising the arms 3, this automatically starting the pipe to rotate due to the shape of 10 these arms. Upon removal from the zinc the pipe runs relatively slowly down the skids 5 and between the rollers 6. Here the pipe is rotated until the zinc solidifies. The pipe is horizontal at all times and the zinc is not wiped from its 15 surfaces. The advantages of this procedure have already been described.

Figures 3 and 4 illustrate the pipe 8 as being provided with caps 9 which may be fixed to the ends of the pipe in any manner, as by a threaded 20 engagement with the same, each of these caps being provided with a concentric opening 10. Assuming the pipe to be fitted with these caps and handled by the apparatus illustrated by Figures 1 and 2 in the aforementioned manner, the 25 pipe receives a thicker coating of zinc inside than it does outside. Obviously, the zinc is uniformly distributed from end to end of the pipe.

I claim:

1. A method of hot-dip galvanized ferrous pipe 30 including dipping the pipe in molten zinc, removing the pipe from the molten zinc in horizontal position and rotating said pipe while continuously maintaining it in a horizontal position during the solidification of zinc on its surfaces. 35

2. A method of hot-dip galvanizing ferrous pipe, including dipping the pipe in molten zinc, removing the pipe horizontally from the molten zinc while positively obstructing its ends to an extent sufficient to retain a greater quantity of 40 zinc inside the pipe than if the ends were completely open and rotating the pipe during solidification of the zinc thus retained inside the pipe.

3. A method of hot-dip galvanizing ferrous pipe, including dipping the pipe in molten zinc, 45 removing the pipe horizontally from the molten zinc and rotating the pipe during its removal from the zinc and thereafter until the zinc retained on the surfaces of the pipe is solidified.

FRANK N. SPELLER. 50

CERTIFICATE OF CORRECTION.

Patent No. 2,124,520.

July 19, 1938.

FRANK N. SPELLER.

It is hereby certified that error appears in the printed specification of the above numbered patent requiring correction as follows: Page 1, second column, line 30, claim 1, for the word "galvanized" read galvanizing; and that the said Letters Patent should be read with this correction therein that the same may conform to the record of the case in the Patent Office.

Signed and sealed this 30th day of August, A. D. 1938.

Henry Van Arsdale
